UNITED STATES PATENT OFFICE.

EDWARD DUDA, OF EDHOLM, NEBRASKA.

POST-PULLER.

1,081,895.

Specification of Letters Patent.

Patented Dec. 16, 1913.

Application filed June 10, 1913. Serial No. 772,889.

To all whom it may concern:

Be it known that I, EDWARD DUDA, a citizen of the United States of America, residing at Edholm, in the county of Butler and State of Nebraska, have invented new and useful Improvements in Post-Pullers, of which the following is a specification.

This invention relates to improvements in post or pole pullers and has particular application to a manually operable pulling device for removing fence posts and the like from the earth.

In carrying out the present invention, it is my purpose to provide a post or pole puller which will embody in its construction among other features a pair of jaws each formed of a single length of rod or the like bent intermediate its length to form a handle, thence extended laterally and downwardly and having the downwardly extended portions curved to form a yoke designed to straddle or embrace the post or pole, the free terminals of the limbs of such yokes being pivotally connected to each other, while the confronting edges of the laterally projecting portions form gripping jaws designed to grip the material of the post or pole.

It is also my purpose to provide a device of the class described which will embrace the desired features of simplicity, efficiency, durability and strength coupled with cheapness of cost in manufacture and marketing and which may be conveniently and readily operated.

With the above and other objects in view, the invention consists in the construction, combination and arrangement of parts hereinafter set forth in and falling within the scope of the claim.

In the accompanying drawing, Figure 1 is a top plan view of a post puller constructed in accordance with the present invention. Fig. 2 is a view in side elevation of the same, and Fig. 3 is an enlarged perspective view of one of the members of the device.

Referring now to the accompanying drawing in detail, the numerals 1, 1 designate companion members forming my im-

proved post or pole puller, each of such members being formed of a single length of iron rod bent upon itself intermediate its ends as at 2 to form a handle 3, thence extended laterally as at 4, 4 and projected downwardly as at 5, 5, the downwardly projecting portions being curved and forming with the laterally projecting portions a yoke. The free terminals of the limbs of the yokes, so formed, are formed with alining apertures to receive pivot pins 6. It will be noted that these yokes, when the members are assembled, enable the device as a whole to be lowered on a pole or post, as clearly illustrated in Fig. 1. When the device is applied to the pole or post, the handles 3 extend outwardly so that they may be readily grasped by the operator, while the confronting sides of the laterally extended portions 4, 4 of the members effectively grip the adjacent portion of the pole so that when an upward pull is exerted upon the members the pole or post is extracted from the earth.

From the foregoing description taken in connection with the accompanying drawing, the construction, mode of operation and manner of employing my invention will be readily apparent. When it is desired to extract a post or pole from the earth, the members 1, 1 are swung about their pivotal connections so as to open the device, whereby the latter may be slipped onto the post. When the device has reached the desired position upon the pole, the members 1, 1 are swung inwardly or toward each other so that the laterally extending portions thereof forming the jaws grip the pole, an upward pressure on the handles serving to elevate the pole. To obtain a fresh grip upon the pole, the pressure is relieved from the handle members thereby permitting the members 1, 1 to swing to an open position whereby the device may be lowered and a fresh grip obtained.

I claim:

A device of the class described comprising companion members, each formed of a single length of iron rod bent upon itself in-

2
termediate of its ends to form a handle, and
thence extended laterally and projected down-
wardly, the downwardly-projecting por-
tions being curved and forming with the lat-
eral projecting portions a yoke, and pivotal
connections between the free extremities of
the yokes so formed.

In testimony whereof I affix my signature
in presence of two witnesses.

EDWARD DUDA.

Witnesses:

JOSEPH A. FICHACEK,
M. STARA.
